CLOTHESLINE ADJUSTER

Eugene Smith Cooper, Augusta, Maine

Application July 24, 1935, Serial No. 32,943

2 Claims.

(Cl. 24—134)

This invention relates to rope clamps and more particularly to a device for adjusting and removing the slack in clothes lines.

The object of the invention is to provide a comparatively simple and inexpensive device of this character capable of being readily positioned on a clothes line and by means of which the clothes line may be conveniently adjusted to the desired tension and securely clamped in adjusted position.

A further object of the invention is to provide a clothes line adjuster which is automatic in action and which will positively grip the line and effectually prevent slippage thereof under all conditions of service.

A further object is to provide a clothes line adjuster including an elongated body portion having a rope receiving recess and provided with a pivoted gripping member for clamping the rope within said recess, there being a finger piece adjacent the gripping member and disposed on the same side of the body portion as said gripping member to facilitate holding the body portion when actuating the gripping member.

A still further object of the invention is generally to improve this class of devices so as to increase their utility, durability and efficiency.

In the accompanying drawing forming a part of this specification and in which similar numerals of reference indicate corresponding parts in all the figures of the drawing,

Figure 1 is a side elevation of a clothes line adjuster embodying the present invention showing the line clamped within the holder.

Figure 2 is a bottom plan view with the rope or clothes line removed.

Figure 3 is a longitudinal sectional view of Figure 1.

Figure 4 is a transverse sectional view taken on the line 4—4 of Figure 1.

Figure 5 is a longitudinal sectional view showing a modified form of the invention.

Figure 6 is a transverse sectional view, taken on the line 6—6 of Figure 5 with the rope or clothes line removed.

The improved clothes line adjuster forming the subject matter of the present invention comprises an elongated body portion 5 preferably cast, stamped, or otherwise formed of metal and having one end thereof provided with an attaching eye 6 to which is secured the adjacent end 7 of a clothes line, as best shown in Figure 1 of the drawing. Depending from the forward end of the body portion 5 are spaced ears 8 defining an intermediate longitudinal groove or

seat 9 for the reception of the other end 10 of the clothes line. Extending through the ears 8 is a transverse pin 11 on which is pivotally mounted a gripping member, indicated at 12. One end of the gripping member is tapered to form an operating handle 13, while the other end thereof is provided with a gripping surface eccentric to the pivot pin 11 and formed with teeth or serrations 14 adapted to bite into the clothes line and firmly clamp the same against the adjacent wall of the seat 9 when said gripping member is swung upwardly to the full line position shown in Figure 1 of the drawing. Extending laterally from the body portion 5 immediately above the ears 8 are oppositely disposed finger pieces 15 preferably slightly dished or curved to accommodate the thumb and first finger of the hand and thus permit the device to be conveniently supported when adjusting the clothes line to remove the slack therefrom. The eye 6 may be fastened to the clothes line or attached directly to a hook, as preferred.

In order to remove slack from the clothes line, the device is grasped in the left hand with the thumb and first finger engaging the finger pieces 15 after which a slight longitudinal pull is exerted on the free end of the line 10 which releases the gripping member 12 and permits said line to slide longitudinally within its seat until all slack has been removed and the line placed under desired tension. When this has been accomplished, the tension on the line will automatically move the gripping member to operative position with the teeth thereof in contact with the rope or line and in which position the clothes line will be firmly held without liability of slippage. It will here be noted that the finger pieces 15 are disposed on the same side of the body portion 5 as the gripping member 12 and are arranged adjacent thereto so that while the device is supported by the thumb and first finger of the operator, the second or middle finger may be used to move the gripping member 12 in the direction of the body portion to effect the automatic clamping of the line in adjusted position.

In Figure 5 of the drawing there is illustrated a modified form of the invention in which the body portion 5' is provided with but a single finger engaging piece, indicated at 16, and this finger piece 16 instead of extending laterally from the opposite sides of the body portion, depends therefrom at the forward end of the body portion, as shown. The gripping member 17 in this form of the device is provided with an elongated handle 18 terminating in a curved finger

piece 19 and the upper walls of the handle and finger piece are preferably curved transversely, as indicated at 20, and of a width greater than the width of the body portion so as to prevent the handle from being forced upwardly within the rope receiving seat 21, as best shown in Figure 6 of the drawing. The construction and operation of the device is otherwise similar to that shown in Figure 1 of the drawing and further description thereof is deemed unnecessary.

It will, of course, be understood that the clothes line adjusters may be made in different sizes and shapes and formed of any suitable material without departing from the spirit of the invention.

It will also be understood that while the adjuster is particularly adapted for application to clothes lines, said adjuster may be used with equally good results as a rope clamp for general purposes.

Having thus described the invention, what is claimed as new is:

1. A device of the class described comprising a body portion having means at one end thereof for attachment to one portion of a clothes line

and provided with a longitudinally disposed seat adapted to receive another portion of said clothes line, ears depending from the body portion at said seat, a gripping member pivotally mounted between the ears and having one portion thereof disposed eccentric to its pivotal axis and provided with teeth and another portion terminating in a handle, and finger pieces extending laterally from opposite sides of the body portion and disposed adjacent the gripping member. 10

2. A device of the class described comprising a body portion having means at one end thereof for attachment to one portion of a clothes line and provided with a longitudinally disposed seat adapted to receive another portion of said clothes line, spaced ears depending from the body portion at said seat, a gripping member eccentrically mounted between the ears and provided with an operating handle of a width greater than the width of the seat, and a finger piece extending 15 laterally from one end of the body portion in advance of the operating handle of the gripping member.
